UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Continuation of application Serial No. 48,525, filed August 6, 1925. This application filed October 2, 1929.
Serial No. 396,652.

The present invention relates to refrigerating apparatus of the compressor-condenser-expander type and is particularly useful in, although not exclusively applicable to, a system using an expansion valve, that is, the so-called dry system, this application being a continuation of my application Serial No. 48,525, filed August 6, 1925.

One of the objects of the invention is to reduce the cost of manufacture of apparatus of this type and at the same time to increase its reliability.

Another object is to provide stable means for controlling the operation of the system in response to the pressure of the refrigerant.

More specifically it is an object of my invention to provide means for controlling the compressor in response to the steady pressure of the refrigerant, that is, the average of instantaneous pressure values over a considerable period of time.

Further objects and advantages of the present invention will be apparent from the following description, reference being had to the accompanying drawings, wherein a preferred form of the invention is clearly shown.

In the drawings:

Fig. 1 is a diagrammatic view of the improved refrigerating system,

Fig. 2 is a view showing a portion of a pressure-time chart on which is indicated the pressure on the low pressure side of the refrigerating system during the operation of the system, and

Fig. 3 is a sectional view, on an enlarged scale, of the expansion valve shown in Fig. 1.

Referring particularly to Fig. 1, a compressor 20 is connected with an inlet pipe 21 and a high pressure outlet pipe 22. Pipe 22 connects with a condenser 23 which is connected by pipe 24 with an expansion valve 25 responsive to the pressure within the evaporator to control the flow of refrigerant into the expansion chamber or evaporator 27. The evaporator 27 includes a pipe coil which is connected by a pipe 29 to a coupling 30 which is connected by the

pipe 21 to the low pressure or suction side of the compressor 20.

The compressor is driven by an electric motor 32 through a belt and pulley connections 33, 34 and 35. The circuit to the motor is controlled by a controller 37 which is responsive to refrigeration demands on the refrigerating system. This controller may be of the type shown in the copending application of Jesse G. King and Sylvester M. Schweller, Serial No. 670,357, filed October 23, 1923. For the purpose of the present invention the diagrammatic showing is deemed sufficient. Control 37 includes an expansible pressure chamber, preferably a metal bellows 38 connected with a source of pressure which is responsive to the refrigerating demand on the apparatus. Bellows 38 actuates an arm through a lever 41 and said arm 40 actuates a snap switch 42 which controls contacts 43 and 44 to open and close the motor circuit.

Referring more particularly to Fig. 3, the expansion valve 25 comprises a casing 50 enclosing a chamber 51 and having an inlet connection 52 and outlet connection 53. Liquid refrigerant supplied through pipe 24 to the connection 52 enters the chamber 51 through an orifice 54 under the control of a needle valve 55 adjustably mounted in a yoke 56 attached to the center of a diaphragm 57. This diaphragm forms one wall of the chamber 51, being sealed to the casing 50 by a clamping ring 58 fastened to the casing by bolts 59. The diaphragm is free to move inward against the force of a spring 60 seated against an annular shoulder 61 on the ring member and bearing against a nut 62 threaded on a stem 63 which passes through the annular shoulder and is secured to the center of the diaphragm 57. The spring normally holds the diaphragm in its central or neutral position with the needle valve 55 seated in the orifice 54 and therefore closing communication between the inlet 52 and chamber 51.

Reduction of pressure with the chamber 51 causes the pressure existing on the outside of the diaphragm to push the latter inward

and open the valve an amount depending on the pressure within the chamber.

The spring 60 is enclosed in a casing 64 preferably formed integral with the ring member 58 and closed by a screw plug 65 which gives access to the adjusting nut 62. A gasket 66 seals the casing 64 providing an air-tight chamber on the outside of the diaphragm, to exclude moisture.

- 10 When the bellows expands due to a refrigerating demand, switch 42 closes the circuit to operate the compressor. This withdraws gaseous refrigerant from the evaporator 27 and pumps it to the condenser 23 where it is condensed to liquid form. The liquid passes through the expansion valve 25 into the evaporator, where evaporation absorbs heat and produces refrigeration. When a sufficient degree of cold has been 20 produced the bellows 38 contracts and stops the compressor.

Pursuant to my invention, I make the operation of the bellows 38 responsive to the refrigerating demand on the system as follows: I transmit the pressure of the refrigerant in the low-pressure side of the system directly to the bellows by a conduit 39 connected to the interior of the bellows at one end and with the evaporator or low-pressure pipe at its other end, preferably at the connection 30.

When refrigeration is needed, the evaporator 27 is warm. Consequently the pressure of the gaseous refrigerant in the evaporator, 35 pipe 29, and compressor crank case is high. This high pressure expands the bellows to start the compressor. Operation of the compressor withdraws gaseous refrigerant from the evaporator and liquifies the refrigerant 40 in the condenser 23. Withdrawal of refrigerant (with consequent reduction of the pressure in the evaporator) opens the needle valve 55 to admit liquid refrigerant from the condenser. The liquid admitted evaporates 45 and produces refrigeration in the well-known manner.

As the evaporator 27 and valve 25 become colder the pressure of air sealed within the casing 64 diminishes which increases the effective force of spring 60 thus changing the setting of the needle valve, causing the latter to close somewhat. Consequently at low temperatures less liquid refrigerant is admitted to the evaporator and the pressure 55 within the latter is less than the pressure at high temperature. This reduction in pressure follows the reduction in temperature making the absolute pressure within the evaporator an indication of refrigerating 60 demand.

The bellows is set to collapse and stop the compressor at a pressure corresponding to the temperature at which refrigeration is no longer required.

65 The difference between the so-called high

and low pressures in the low pressure side, that is, the difference between pressures which will start and stop the compressor, is quite small, being of the order of one or two pounds per square inch. Consequently

70

the pressure-responsive controlling means must be quite sensitive and adjusted to operate on small differences of pressure. This necessary characteristic will produce unreliable operation due to slight fluctuations in

75

pressure within the system, unless provision is made for eliminating the effect of such fluctuations. There are various causes of such fluctuations. In the first place, it

80

has been found that when the compressor starts it may either remove a considerable quantity of refrigerant from the evaporator 27 and pipe 29 before the valve 25 opens, or for a brief interval withdraw refrigerant from the evaporator faster than it flows

85

through valve 25. This condition may momentarily reduce the pressure in the low-pressure side to the value at which the bellows opens the switch, without producing appreciable refrigeration. If the switch

90

were allowed to open at this point, no refrigeration would ever be produced. But if the switch is held closed for a moment, refrigerant enters the evaporator and its vapor

95

increases the pressure in the system to a value between the starting pressure and stopping pressure. The compressor will then continue to withdraw gas from the low-pressure side of the system, tending to reduce the pressure, and refrigerant flowing

100

into and evaporating in the expansion chamber will tend to increase the pressure, thus maintaining a balance or steady pressure in the system. Secondly, it has been found that when the pressure is near the stopping

105

value, the strokes of the piston in a compressor of the reciprocating type, may cause instantaneous low pressures which would, if transmitted to the bellows, permit it to collapse and stop the compressor before the steady pressure in the system justified stopping.

110

Thirdly, drops of oil in the evaporator tubing may cause fluctuations in pressure.

115

To eliminate the effect on the switch of these momentary low pressures, the passage through the conduit 39 is made sufficiently small to offer a considerable resistance to the flow of gas through it. Incidentally the

120

volume of the bellows is preferably by comparison, very large. This arrangement results in interposing an appreciable time between a sudden change of pressure in the tube 29 and its resulting change of pressure in the bellows. This dampens out

125

pressure pulsations due to reciprocation of the piston, and prevents the momentary reduction of pressure on starting the compressor from reaching the bellows. Consequent-

130

ly the bellows is insensitive to sudden changes of pressure in the pipe 29, being responsive only to the steady pressure of the refrigerant. As an example, a conduit approximately seven feet long having an internal diameter of one twentieth of an inch has been found to offer sufficient resistance to the passage of gas to dampen out pulsations of pressure produced in a single cylinder reciprocating compressor having a displacement of approximately three and one half cubic inches and operating at a speed of 400 revolutions per minute.

Referring to Fig. 2, the lines A indicating time and the lines B to the left of "O" line indicating pressure in pounds above atmospheric, and those to the right of "O" indicate vacuum measured in inches of mercury. The lines X, Y and Z indicate the pressure within the low pressure side of the refrigerating systems, when SO_2 is used as the refrigerant. Considering one cycle of operation of the refrigerating system, the compressor is rendered operative when the pressure within the low pressure side attains a certain high value herein shown in approximately eight pounds gauge and which is indicated at Z'. The operation of the compressor will lower the pressure in a relatively short length of time as indicated by line X so that the pressure therein is equal to approximately five inches of vacuum. This point is indicated at X'. At this pressure, the expansion valve 25 will permit more refrigerant to enter the evaporator whereby the value of pressure within the evaporator tends to remain constant. However, for the reason previously stated, the pressure within the low pressure side of the system adjacent the compressor 20 gradually decreases as is indicated by line Y. The length of the line Y measures the time during which the expansion valve is open and hence measures the time during which refrigeration is produced. The point Y' indicates the pressure value corresponding to a temperature which is sufficiently low that refrigeration is no longer required, and consequently at which the bellows collapses to open the switch. As shown in Fig. 2 this value is a vacuum of seven inches of mercury. From the point Y' the curve Z indicates a rise of pressure in the evaporator due to an increase of temperature of the evaporator when the compressor is not running.

It will be appreciated from Fig. 2 that the pressure limits X' and Y', between which refrigeration is produced, are very close together, the total pressure difference in the low pressure side of the system during the refrigerating phase of the operating cycle being in the present case only about two inches of mercury. The pressure variations caused by the operation of the compressor may be and usually are greater than this

pressure difference. Consequently if these pressure variations were permitted to act on the bellows 38 at the time when the mean pressure is so close to the stopping value, the switch would open at some point along the curve Y between the points X' and Y' and might even open at the point X'. It will be readily seen that if the switch is open before the steady pressure reaches the point Y' that an insufficient amount of refrigeration will be produced and that the compressor might even operate indefinitely without producing any refrigeration.

The tube 39 in permitting only the mean or steady pressure to act on the bellows insures operation of the compressor in strict accordance with the refrigerating demand, and produces a simple, reliable and economical control device. The line Z indicates the rise in pressure on the low pressure side when the compressor is inoperative.

While the form of embodiment of the present invention as herein disclosed, constitutes a preferred form, it is to be understood that other forms might be adopted, all coming within the scope of the claims which follow.

What is claimed is as follows:

1. Refrigerating apparatus including in combination an evaporating chamber, means responsive to the pressure of the evaporating chamber for admitting liquid refrigerant thereto, means for withdrawing gaseous refrigerant from the chamber, means responsive to a decreasing temperature of the evaporating chamber for modifying the action of the admitting means to reduce the pressure of the evaporator, means responsive to the pressure of the refrigerant for controlling the withdrawing means, and means for preventing sudden changes of pressure from affecting the controlling means.

2. Refrigerating apparatus including in combination an evaporating chamber, means responsive to the pressure of the evaporating chamber for admitting liquid refrigerant thereto, means for withdrawing gaseous refrigerant from the chamber, means responsive to a decreasing temperature of the evaporating chamber for modifying the action of the admitting means to reduce the pressure of the evaporator, pressure responsive means exposed to the pressure of the refrigerant for controlling the withdrawing means, and dampening means associated with the pressure responsive means to prevent sudden changes of pressure from affecting the controlling means.

3. Refrigerating apparatus including in combination an evaporating chamber, means responsive to the pressure of the evaporating chamber for admitting liquid refrigerant thereto, means for withdrawing gaseous refrigerant from the chamber, means re-

sponsive to a decreasing temperature of the evaporating chamber for modifying the action of the admitting means to reduce the pressure of the evaporator, pressure responsive means exposed to the pressure of the refrigerant for controlling the withdrawing means, and means interposing a time interval between a change in pressure of the refrigerant and the resulting operation of the controlling means.

4. Refrigerating apparatus including in combination an evaporating chamber, means responsive to the pressure of the evaporating chamber for admitting liquid refrigerant thereto, means for withdrawing gaseous refrigerant from the chamber, means responsive to a decreasing temperature of the evaporating chamber for modifying the action of the admitting means to reduce the pressure of the evaporator, pressure responsive means exposed to the pressure of the refrigerant for controlling the withdrawing means, and means interposing a time interval between a change in pressure of the refrigerant and the resulting change in pressure in the pressure responsive means.

5. Refrigerating apparatus including in combination means containing refrigerant, means responsive to the pressure of the containing means for admitting liquid refrigerant thereto, a reciprocating pump for withdrawing refrigerant therefrom, means responsive to a decreasing temperature of the containing means for modifying the action of the admitting means to reduce the pressure of the evaporator, means responsive to the pressure of the refrigerant for controlling the pump, and means preventing pulsations in pressure caused by the pump from affecting the control means.

6. Refrigerating apparatus comprising in combination means containing a refrigerant, means responsive to the pressure of the containing means for admitting liquid refrigerant thereto, means for withdrawing refrigerant therefrom, means responsive to a decreasing temperature of the containing means for modifying the action of the admitting means to reduce the pressure of the evaporator, controlling means for the withdrawing means, an expansible pressure chamber for operating the controlling means, a conduit connecting the pressure chamber with the containing means, the area of the passage through the conduit being sufficiently small to dampen out pulsations of pressure of the refrigerant.

7. Refrigerating apparatus comprising in combination means containing a refrigerant, means responsive to the pressure of the containing means for admitting liquid refrigerant thereto, means for withdrawing refrigerant therefrom, means responsive to a decreasing temperature of the containing means for modifying the action of the ad-

mitting means to reduce the pressure of the evaporator, controlling means for the withdrawing means, an expansible pressure chamber of relatively large volume for operating the controlling means, a conduit having a passage of relatively small area connecting the pressure chamber with the containing means, the relation between the area of the passage and volume of the pressure chamber being such as to provide a substantial time interval between a change of pressure in the containing means and the resulting change of pressure in the pressure chamber.

8. Refrigerating apparatus comprising in combination means containing a refrigerant, means responsive to the pressure of the containing means for admitting liquid refrigerant thereto, means for withdrawing refrigerant therefrom, means responsive to a decreasing temperature of the containing means for modifying the action of the admitting means to reduce the pressure of the evaporator, pressure responsive means for operating the withdrawing means, a conduit connecting the containing means with the pressure responsive means, said conduit being adapted to dampen out pulsations of pressure of the refrigerant.

9. Refrigerating apparatus comprising in combination means containing a refrigerant, means responsive to the pressure of the containing means for admitting liquid refrigerant thereto, means for withdrawing refrigerant therefrom, means responsive to a decreasing temperature of the containing means for modifying the action of the admitting means to reduce the pressure of the evaporator, pressure responsive means for controlling the withdrawing means, and a conduit connecting the containing means and the pressure responsive means, the length of the conduit being such as to interpose resistance to fluid flow sufficient to dampen out pulsations in pressure of the refrigerant.

10. Refrigerating apparatus including in combination an evaporating chamber, means responsive to the pressure of the evaporating chamber for admitting liquid refrigerant thereto, means for withdrawing gaseous refrigerant from the chamber, means responsive to a decreasing temperature of the evaporating chamber for modifying the action of the admitting means to reduce the pressure of the evaporator, snap acting means for controlling the withdrawing means, and means for operating the snap acting means in response to the pressure in the chamber, said operating means being insensitive to sudden changes of pressure in the evaporating chamber.

In testimony whereof I hereto affix my signature.

HARRY B. HULL.
